UNITED STATES PATENT OFFICE

ELMER FERNSTROM, OF LA JOLLA, CALIFORNIA

METAL FURRING STRIP

Application filed December 15, 1930. Serial No. 502,460.

My invention relates to improvements in metal furring strips which provide for attaching metal or wire lath thereto so as to provide a sufficient space between the wire 5 lath and the sheathing or other wall structure, to allow the plastic material to enclose the metal lath securely, whereby the wall structure when the plastic material is dried, will not crack or break. I accomplish these 10 objects by the structure illustrated in the accompanying drawing, in which:

Figure 1 is a detailed view in perspective of my improved metal furring strip shown on a wall with a metal fabric placed thereon 15 in position to be attached thereto, and showing the mode of such attachment, and

Figure 2 is a cross sectional view of a plaster or stucco wall and sheathing showing my furring strip mounted on the sheathing in 20 said wall and the metal fabric mounted in the furring strip. Similar numerals refer to similar parts throughout the several views.

My invention consists of the member 1 which is provided with the portion 2, portion 25 3, and the portion 4.

The member 1 is made of a metal strip of such a gauge and width as may be desired and it is shaped by longitudinally bending or folding the portion 2 at a right angle to 30 the portion 3 and similarly bending or folding in the opposite direction to the portion 3, the base portion 4.

The portion 2 is provided with a plurality of cleats 5 made by cutting a segment of said 35 portion 2 therefrom and from the portion 3 so as to allow the said cleats 5 to be bent to a position perpendicular to the edge of said portion 3.

The portion 3 is of a width to provide the 40 desired space between the metal fabric 6 and the sheathing 7 to permit the plastic material when applied to properly enclose and surround the metal fabric 6 and fill the space between said metal fabric 6 and the sheath- 45 ing 7. The said portion 3 is also provided with openings 8, spaced apart throughout its length which are adapted to further reinforce the wall structure and to provide for contraction and expansion of the wall structure.

The portion 4 is provided with a plurality of holes 10 spaced apart throughout its length which are adapted to receive nails or other means for securing said member 1 to the said sheathing 7 or to the studding in case sheath- 55 ing is not used in the construction.

In use, the desired number of members 1 are placed on the sheathing 7 or studding in a vertical position so that the ends 9 of said members 1 will be at the top, thereby 60 allowing the metal fabric 6 to rest on the cleats 5 when they are projecting from the member 1, and said cleats 5 are then bent back by use of a hammer or other means to their former position on the edge of the portion 3 65 so as to hold said metal fabric 6 securely against the edge of portion 3 of said member 1.

It will thus be noted that my invention provides a continuous spacing portion be- 70 tween the metal fabric 6 and the sheathing 7 or other wall structure, thus providing a rigid support for the metal fabric 6; that by means of the cleats 5 the metal fabric 6 is se- 75 curely held in position against the member 1; that openings 8 provide for better re-en- 80 forcement of the structure, and reduces the possibility of cracking or breaking through contraction or expansion of the plastic struc- 85 ture.

What I claim and desire to secure by Letters Patent is:

1. A furring strip comprising an elongated flat base adapted to be secured to a sheath- 85 ing or studding of a wall structure, a rib or web extending forwardly from the base for the entire length thereof and arranged at one edge of the base, said rib or web being adapt- 90 ed to support a wire mesh reinforcing fabric on its outer edge in spaced relation with re- 95 spect to the sheathing or studding, said rib or web being formed at spaced intervals with plastic receiving openings, a flange extending laterally from the outer edge portion of the 95 rib or web and disposed in an opposite direc- 100 tion with respect to the base, said flange being slotted at spaced intervals to form bend- able cleats for securing the wire mesh fabric in position on the furring strip.

2. A furring strip comprising a flat elongated metallic base adapted to be secured to a sheathing or studding of a wall structure, a rib or web extending forwardly from one edge portion of the base and disposed at right angles thereto, vertically spaced segments extending laterally from the outer edge of the rib or web and disposed in opposite directions to the base, and pliant cleats extending forwardly from the upper ends of the spaced segments to provide supporting means for a reinforcing metal fabric, the fabric being secured against the outer edge of the rib or web when the cleats are bent over the adjacent portions of the fabric.

3. A furring strip comprising a flat elongated metallic base adapted to be secured to

a sheathing or studding of a wall structure, a rib or web extending forwardly from one edge portion of the base and disposed at right angles thereto, vertically spaced segments extending laterally from the outer edge of the rib or web and disposed in opposite directions to the base, and pliant cleats extending forwardly from the upper ends of the spaced segments to provide supporting means for a reinforcing metal fabric, the fabric being secured against the outer edge of the rib or web when the cleats are bent over the adjacent portions of the fabric, said rib or web being formed at spaced intervals with plastic receiving openings.
